CARRIER FOR ROLLS OF TOILET PAPER
AND LIKE ROLLSCornelis Franciscus Maria van Berkel, Wassenaar,
near The Hague, Netherlands, assignor to
Vincent Joseph Marie Eras, Dordrecht, NetherlandsApplication March 13, 1934, Serial No. 715,298
In Great Britain March 9, 1933

5 Claims. (Cl. 242—55.2)

This invention relates to carriers for rolls such as rolls of toilet paper and of the type in which a roll can be placed on a movable support, pivoted to a wall, which exercises a frictional braking action upon the roll, thereby maintaining it stationary normally and restraining its motion during unwinding. The wall may be formed by a back member or by the wall of the room to which the carrier is attached.

10 One object of the present invention is to provide a generally improved carrier of the aforesaid type, which will be simple to make.

Another object of the invention is to provide a carrier in which a roll may be easily inserted.

15 Still another object is to provide a carrier of such construction that an inserted roll cannot slide out of the carrier due to movement of the wall or backing member, which may happen e. g. in cars and other vehicles, on board ships and 20 aeroplanes.

In the carrier according to the invention the support comprises a pin, on which the roll can be applied by extending the pin into a bore of the roll, said pin cooperating with a movable stop, which moves corresponding to a movement 25 of the pin, in respect to the wall to which the carrier is attached, such that the roll is prevented in any case from leaving the pin.

The stop may form part of the pin or it may 30 be constituted by a separate movable member. In the first case the stop may consist of a hook-shaped end of one leg of a U-shaped support, said leg forming the pin.

In the latter case the separate member may 35 consist of a front plate, which is adapted to press against the pin-supported roll, such as to obtain at the same time an increased braking effect, which is particularly desirable when only a small amount of paper or the like remains in the roll. 40 The front plate may be provided with upstanding flanges forming the stop. In addition, the said member may be made to serve as a cover in order to prevent dust and other contaminating matter from being deposited upon the roll and the 45 exposed surfaces of the back member and roll-support. Moreover the front member may be so made as to enhance the appearance of the holder.

50 It should be noted that the stop according to the invention should follow in some way the motion of the roll-support. If e. g. the stop would be applied as a fixed stop to the backing member, the roll may still glide from the pin upon movement from the wall, a position of the roll being

possible in which same is removed a considerable distance from the wall.

Preferably the front member is suspended from the same axis as the roll support, so that the back member, support and front member are 5 all relatively pivotal about the said axis.

A lost-motion connection may be provided between the separate member and the roll-support, the said connection being such that it permits the front member to be freely rotated through 10 a certain angle until a positive interconnection is established after which the front member is accompanied by the roll support in any further rotating or lifting movement.

If a back member is provided, this may also 15 have forwardly directed side flanges, which would fit neatly against the inner faces of the first mentioned side flanges and would be far enough apart to leave adequate working clearance for the ends of the roll.

20 The flanges also serve as partial side covers for the roll.

In the drawing:

Figure 1 is a front elevation of one embodiment of the carrier according to the invention; 25

Figure 2 is a side view of the same embodiment.

In the drawing, there is shown a paper roll 1, a U-shaped roll-support 8, a back member 9 and a front-plate 10. The horizontal limbs of the 30 roll-support 8 are indicated at 11 and 12. The roll 1 is carried by the limb 12.

The limb 11 is rotatable about pivots, formed by the flat ends of screws 13, which pass through axial holes in the ends of the limb 11 and which are screwed in forwardly extending side flanges 14 of the flat back plate 9. The front member 10 is also constituted by a substantially flat plate with rearwardly extending side flanges 15. The support 8 and the plates 9 and 10 are connected pivotally about the main axis of the limb 11, the plate 10 being rotatable about the screws 13. The flanges 14 and 15 are provided such that the carrier (when no roll is inserted) can be folded together the inner surfaces of the 45 flanges 15 fitting then neatly over the outer surfaces of the flanges 14.

It can be seen in the drawing that the roll supported in the limb 12 is enclosed between the support 8 and the side flanges 14 and 15, which form also partial covers for the roll. The top of the front plate 10 is arcuate and passes partly around the pivots 13. In this arcuate part at one side a slit 16 is provided, through which extends a pin 17, which is fixed to the limb 11. 55

This pin and slot connection forms a lost-motion connection between the support 8 and the plate 10, the plate 10 being enabled to be lifted first until the roll 1 is freed from the flanges 5 15 and thereafter the support 8 is carried off with the plate, when a wall part of the slit 16 abuts against the pin 17. Then the roll may be taken from the limb 12 and replaced by a new one.

After lowering the plate 10 the roll is pressed 10 against the back member and the carrier is again in readiness for use.

It is to be understood that the invention is applicable to holders having other forms of roll-support. For example the roll support may be 15 approximately of inverted U-shape, with inturned bottom ends engaging a roller adapted to be passed through the bore of the roll.

What I claim is:

1. Carrier for rolls of toilet-paper and like 20 rolls consisting of a movable support for the roll, said support comprising a pin, on which the roll can be applied by entering the pin into a bore of the roll, a movable front cover plate with which the pin cooperates and which is adapted 25 to press the pin supported roll on to a wall, said front plate being provided with a stop for limiting longitudinal movement of the roll.

2. Carrier for rolls of toilet-paper and like 30 rolls consisting of a movable support for the roll, said support comprising a pin, on which the roll can be applied by entering the pin into a bore of the roll, a separate member to which the roll support is connected, and a stop associated 35 with said separate member for limiting longitudinal movement of the roll including a lost motion connection such that the member is freely rotatable over a certain angle and afterwards rotates the roll support.

3. Carrier for rolls of toilet-paper and like 5 rolls consisting of a movable support for the roll, said support comprising a pin on which the roll can be applied by entering the pin into a bore of the roll, a movable front plate to which the roll support is connected, said front plate being provided with upstanding flanges acting as a stop and suspended from the same axis as the roll support, and a connection between said roll support and said front plate of the lost-motion 10 type such that the front plate is freely rotatable over a certain angle and afterwards carries off the roll support.

4. Carrier for rolls of toilet-paper and like 15 rolls consisting of a movable support for the roll, said support comprising a pin on which the roll can be applied by entering the pin into a bore of the roll, a movable front plate to which the roll support is connected, said front plate being provided with upstanding flanges acting as a 20 stop and suspended from the same axis as the roll support, a connection between said roll support and said front plate being of the lost-motion type such that the front plate is freely rotatable over a certain angle and afterwards carries off 25 the roll support, and a back member being provided having forwardly directed side flanges which fit neatly against the inner surfaces of the flanges of the front plate.

5. A holder for a roll of toilet paper and the 30 like comprising a back member adapted to be secured to a wall, a roll support pivoted to said back member having a pin portion adapted to enter the bore of the roll, and a front roll covering plate pivotally supported to bear by gravity 35 against the roll to apply frictional resistance against rotation of the roll.

CORNELIS FRANCISCUS MARIA
VAN BERKEL.
